UNITED STATES PATENT OFFICE

HENRY C. KUHNHEIM, OF NEWPORT, KENTUCKY

BELT BUCKLE

Application filed March 7, 1928. Serial No. 259,805.

This invention relates to an improved form of belt buckle of the type in which the free end of the belt is insertable and capable of being fixed at any point between the inner 5 face of the buckle and the co-operating clamping means.

An object of the invention is to provide a belt buckle which in clamped position entirely prevents slipping of the belt therethrough. 10 Another object is to provide a buckle with a minimum of parts, making for simplicity and economy in manufacture.

Other objects and relationships will be apparent in the following specification and its 15 accompanying drawings, of which latter:

Fig. 1 is a plan view of the under side of the buckle and a portion of the belt.

Fig. 2 is a cross sectional view of the buckle taken on line 2—2 of Fig. 1.

20 Fig. 3 represents the clamping detail of the device.

Fig. 4 is an enlarged view on line 2—2 of Fig. 1, showing belt and buckle in operative position.

25 Fig. 5 is an enlarged perspective view of the clamp.

Preferably the buckle is manufactured from sheet metal. In the drawings numeral 1 points out the buckle plate; 2, the guideways formed by bending two equal and opposite portions of the plate into L shape in cross section and bringing one of the faces of each of the portions thus bent into spaced parallelism with the under face of the plate.

30 The belt clamp 3, is the second and only other member of the buckle. It is stamped from a sheet of metal and has a base 4 with a loop section extending therefrom. This loop section has an arm 5 parallel to the base, around which the belt 6 is looped and secured as shown in Fig. 1. The base 4 is formed into a channel, U-shaped in cross section, the sides 13 and 14 of which channel are turned up substantially at right angles with the plane of the remainder of the belt clamp. Pivot studs 7 extend outwardly from and in parallel relation with, the bottom portion of the channel-like base 4. The side of this channel which is nearest the arm 5 has extending from its 45 top edge, 8, two spurs, 9, the formation of

which is effected by extruding two spurs from the edge of the top before the base is given its U-shape. These spurs, due to the fact that they are extruded rather than cut, are offset relative to the longitudinal center of the top 55 edge 8 and have depressions immediately adjacent their longitudinal sides in the said top edge of the channel. Said depressions are designated by the numeral 12. The other edge, 10, of the channel is plain, without indentations or spurs, but slightly beveled in the direction away from the opposite side of the channel. If desired, however, both edges may be similarly indented and spurred.

The connection and interaction of plate 1 and clamp 3 will now be explained. It has been pointed out that the guideways, 2, are L-shaped in cross section. At one end of each guideway and at the junction of the cross sectional L's thereof a short longitudinal cut 60 is made so as to allow the portion of the guideways thus cleared to be rolled inwardly upon themselves as shown at 11 in Fig. 2. The two opposite rolled portions 11 form 65 bearings, in which are pivoted the pivot studs, 7 of the clamp 3. In positioning the clamp 3, the open channel of base 4, is faced 70 inwardly towards the buckle plate, 1.

In use, the free end of the belt is introduced 75 between the guideways 2 and the buckle plate 80 1 at the side opposite the clamp. While the free end is being thus inserted the clamp 3 is pivotally turned downwardly or away from the buckle plate, 1. This causes the integral base 4, and its channel to assume a side- 85 wise position, giving clear passageway to the belt; when the free end of the belt has been 90 inserted to a desired length the clamp is re-turned to its operative position most clearly seen in Fig. 2. It is apparent that the two 95 edges, 8, and 10, of base 4, are thus brought into firm contact with the belt, forming, the one with its beveled edge and the other with its spurred edge, a doubly secure and non-slipping arrangement. The reverse process, of course, is used in releasing the end of the belt.

Having thus set forth the structure and operation of the buckle, what is claimed is:

1. A belt buckle comprising a plate two 100

opposite edges of which are similarly bent to form belt guideways, L-shaped in cross section, those portions of the guideways parallel to the buckle plate being longitudinally cut for a short space at the point of juncture with the plate and the cut away parts thus formed being rolled inwardly upon themselves to form a pair of oppositely disposed bearings; and a clamp stamped from a single sheet of material and comprising a base with a loop portion extending therefrom, the base and the arm provided by the loop portion being parallel, the longitudinal sides of the base being turned upwardly at substantially right angles with the plane of the remainder of the clamp and forming thereby a channel along one of whose top edges spurs are extruded, the other edge being beveled in a direction away from the opposite side of the channel, and from either end of which base extend pivot pins by which the clamp is pivoted onto the bearings formed on the plate as above.

2. A belt buckle comprising a plate having strap guideways with oppositely disposed bearings thereon; and a clamp member pivoted in the bearings, the clamp member having a base with a loop portion extending therefrom, the longitudinal sides of the base being turned up in the direction of the plate, one of said sides having spurs along its top edge, said spurs being offset relative to the longitudinal center of said top edge, the top edge of the opposite side being beveled in a direction away from the side providing the spurs.

3. A belt buckle comprising a plate having guideways and bearings thereon, and a clamp member pivoted in said bearings and having sides extending in the direction of the plate, one of said sides having spurs extruded from its top and offset relative to the longitudinal center thereof.

4. A belt buckle comprising a plate member with a clamp member pivoted thereon, the clamp member having sides extending in the direction of the plate, the longitudinal edge of one of said sides having spurs offset relative to the longitudinal center of said edge and depressions adjacent thereto.

5. A belt buckle comprising a plate member with strap guideways and bearings formed thereon, and a clamp member pivoted in said bearings and having a channeled base with two sides extending in the direction of the plate, one of the sides being beveled along its top edge, the other side having spurs on its edge and offset relative to the longitudinal center thereof and depressions adjoining the longitudinal sides of the spurs.

6. A belt buckle comprising a plate with strap guideways and bearings thereon; and a clamp pivoted in said bearings and comprising a base in channel form with a loop portion extending therefrom, the longitudi-

nal sides of the channel being turned upwardly at substantially right angles with the plane of the remainder of the clamp, that side adjacent the loop portion having spurs on its edge and offset relative to the longitudinal center thereof and depressions adjacent thereto, said edge being adapted to assume an increasing proximity to the plate upon pivotal movement of the clamp from an angular to a parallel relation with the plate.

In testimony whereof, I have hereunto subscribed my name this 1st day of March, 1928.

HENRY C. KUHNHEIM.
